(57) **CLAIM**

The ornamental design for a guard for hair removal device, as shown and described.

DESCRIPTION

FIG. 1 is a front perspective view of a guard for hair removal device of the present invention showing our new design; FIG. 2 is a front view thereof;

FIG. 3 is a rear view thereof;

FIG. 4 is a side view thereof, the opposing side view being a mirror image thereof;

FIG. 5 is a top plan view thereof; and,

FIG. 6 is a bottom plan view thereof.

The broken lines illustrate portions of the guard for hair removal device and form no part of the claimed design.
